FOREIGN PATENT DOCUMENTS

JP 2013052094 A 3/2013

Primary Examiner — Mary Ann Calabrese(74) *Attorney, Agent, or Firm* — Edell, Shapiro & Finnian, LLC(57) **CLAIM**

The ornamental design for an infant support pillow, as shown and described.

DESCRIPTION

FIG. 1 is a top perspective view of an infant support pillow according to the present invention;

FIG. 2 is a top view of the infant support pillow of FIG. 1; FIG. 3 is a bottom view of the infant support pillow of FIG. 1;

FIG. 4 is a front view of the infant support pillow of FIG. 1; FIG. 5 is a rear view of the infant support pillow of FIG. 1; FIG. 6 is a right side view of the infant support pillow of FIG. 1; and,

FIG. 7 is a left side view of the infant support pillow of FIG. 1.

The broken lines shown in the figures are included for the purpose of illustrating the unclaimed portions of the article and form no part of the claimed design.
